UNITED STATES PATENT OFFICE.

THOMAS J. WALSH, OF WALTON, KENTUCKY.

SIGNAL-LAMP-RAISING DEVICE.

SPECIFICATION forming part of Letters Patent No. 629,222, dated July 18, 1899.

Application filed May 12, 1899. Serial No. 716,603. (No model.)

To all whom it may concern:

Be it known that I, THOMAS J. WALSH, of Walton, in the county of Boone and State of Kentucky, have invented a new and Improved 5 Signal-Lamp-Raising Device, of which the following is a full, clear, and exact description.

This invention relates to devices for raising and lowering signal-lamps at railway-stations.

It is a common practice to place signal- 10 masts on the roof or similar support of a railway-station house. To reach the base of the masts, a portable ladder is used. Then the person in order to adjust the signal-lantern upon the top of the mast must climb a narrow 15 ladder secured to the mast, which is necessarily vertical, or nearly so. This operation not only consumes time, but sometimes it is extremely dangerous and, in fact, is not to be accomplished at all by a cripple or infirm person. When such infirm person is employed 20 as a telegraph-operator and ticket-agent, it is necessary to employ another man to attend to the signal-lamp, and this adds a considerable amount to the running expenses of a road.

The object of my invention, therefore, is 25 to provide a simple and comparatively inexpensive apparatus by means of which the signal-lamps may be raised and lowered by an operator while sitting in the office or station 30 or standing on the ground or platform outside the building, thus obviating the danger to life and limb above mentioned and also making it feasible to employ women as telegraph-operators and ticket-agents, as the duty attending 35 the signals devolves upon such operators or agents.

I will describe a signal-lamp-raising device embodying my invention and then point out the novel features in the appended claims.

Reference is to be had to the accompanying 40 drawings, forming a part of this specification, in which similar characters of reference indicate corresponding parts in all the figures.

Figure 1 is side elevation of a mast, showing 45 a device embodying my invention applied thereto and operated from the outside of the building or station. Fig. 2 is a partial side elevation of the same, showing the lamp in place. Fig. 3 is a side elevation of the same, 50 partly in section, showing the arrangement for operating the device from the inside of the building. Fig. 4 is a sectional elevation of a

portion of the device, and Fig. 5 is a rear elevation thereof.

Referring to the drawings, 1 designates a mast on which the usual semaphore-signals 2 2° are mounted. These semaphores, however, form no part of my present invention. Attached to one side of the mast at its top is a casting 3, which, as here shown, is made in skeleton form—that is, it comprises two side members connected by a cross-bar at the bottom and by a cross-bar intermediate the ends. A lever 4 is fulcrumed in the upper portion of this casting 3. This lever 4 has a part 5, 65 turned at right angles to the body portion, and in this part 5 is fulcrumed a pulley 6, around which may be placed a guard 7 to prevent the slipping off of a rope or other device 8 for the lantern 9. To prevent the lantern 7° from swinging relatively to the rope, it may be provided with an eye 10, through which the rope passes. To the opposite end of the lever 4 is attached a lever-swinging rope 11.

The top of the mast 1 is made to engage in 75 the hollow bottom of the lantern 9 when said lantern is in place, thus holding it from movement, and for conveniently guiding the lantern to its seat I provide guide-fingers 13, which extend upward from the sides of the 80 mast. These guide-fingers are curved slightly outward at their upper ends and are particularly useful during high winds that would deflect the lantern from its proper course to engage upon the mast. As a further means for 85 holding the lantern securely in place I employ a rod 14, which is attached to and forms part of the mast 1 and is designed to engage in a socket 15, attached to the upper portion of the lamp.

In Fig. 1 I have shown the ropes 8 and 11 as extended to a place outside the station or building. In Fig. 3, however, the ropes are extended through a hatch 16, leading through the roof of the station-house or through the 95 roof of the bay-window usually connected to the station-house. Therefore the device may be operated by a person sitting in the office. The hatch 16 is provided with an upwardly- 100 swinging cover 17, which may be raised and lowered by any desired means, and this cover is provided with glass 18, so that an operator by looking upward may ascertain whether or not the lamp is burning.

In operation by pulling upon the rope 8 the lamp will be raised substantially to the position indicated in Fig. 1. Then by pulling upon the rope 11 the lever 4 will be swung upward, so that its right-angled portion 5 and the pulley will be directly over the center of the mast. Then by loosening the rope 8 the lantern will be lowered onto the end of the mast, as indicated in Fig. 2. While I have shown the mast as connected to a building, it is obvious that it may be otherwise placed—for instance, in the ground alongside the track.

Having thus fully described my invention, I claim as new and desire to secure by Letters Patent—

1. In combination with a mast, a signal-lamp-raising device, comprising a lever at the upper end of said mast, a pulling device extended downward from one end of said lever, a pulley carried by the other end of said lever, and a rope or the like extending around said pulley and adapted for connection with the lamp, substantially as specified.
2. The combination with a mast, of a fulcrum-casting thereon, the guide-fingers ex-

tended upward from the top of the mast, a lever fulcrumed in said casting, a rope extended from one end of said lever, and a pulley pivoted in a portion of said lever extended at an angle from the main portion of the lever, 30 a rope extending around said pulley and adapted for connection with the lantern, and a guard to prevent the rope from slipping off the pulley, substantially as specified.

3. The combination with a mast, of a fulcrum-casting on the upper end of the mast, said casting being in skeleton form, a lever fulcrumed in said casting, a rope extended from one end of the lever, a pulley pivoted in a portion of said lever extended at an angle 40 from the main portion of the lever, a rope extending around said pulley and adapted for connection with the lantern, and a rod extended upward from the mast and adapted to engage in a socket on the lantern, substantially as specified.

THOMAS J. WALSH.
